MAX LANGER, OF HERMSDORF, NEAR BERLIN, GERMANY, ASSIGNOR TO SIEMENS & HALSKE AKTIENGESELLSCHAFT, OF WERNERWERK, SIEMENSSTADT, NEAR BERLIN, GERMANY

CIRCUIT ARRANGEMENT FOR AUTOMATIC TELEPHONE SYSTEMS

Application filed August 12, 1927, Serial No. 212,456, and in Germany January 31, 1927.

In automatic telephone systems a certain and faultless emission of current impulses is dependent to a large extent on the switching times of the impulse-storing relay. Known already are arrangements in which the impulse storing relay is connected in a more sensitive circuit during the sending out of impulses. With such arrangements however one of the switching periods of the relay is 10 unfavorably influenced.

The purpose of the invention is to bring about that with each condition of energization of the relay the switching time necessary for obtaining the other condition of energization shall be curtailed and this is accomplished by the impulse-storing relay so acting upon its own circuit that with each state of energization (either energized or de-energized) there is present a condition of current which is adapted to bring about a rapid attainment of the other condition of energization.

The drawing shows an example of the invention in the form of the circuit of a group selector. Assuming that the group selector has been engaged by any switching device allotted to it, then the relay C will be energized. Consequently the contacts c1 to c4 are operated. The contact c1 connects 20 the winding II of the relay C to the e wire. The contact c2 applies earth to the circuit for the lifting magnet H. The latter however is not energized because, during the engagement of the group selector the line relay A and the release relay B at the lines a and b are energized. The energizing circuit for the relays A and B runs from battery, winding of the relay A, a-wire, over the pre-selecting member (not shown), subscriber's 30 loop to the b wire, winding II of the relay B, contact a2, of the relay B, earth. The relay B through its contact b1 opens the short circuit of the winding II of the relay C. Relay A opens, through its contact a1 40 the circuit for the lifting magnet H. If, by using his dial switch, a subscriber sends out a series of impulses, then during a first interruption of the loop the relay A will be made to retract; since the contact a2 is open 50 when the relay A is energized, the latter rap-

idly retracts owing to the inserted resistance of the winding I of the relay B in the energizing circuit of the relays A, B. Passing over contact a1, the lifting magnet receives an impulse of current. If now the loop is again closed over the lines a, b, the conditions of current in the circuit of the relays A, B, by short circuiting the winding I of the relay B through the contact a2, are of such a kind that the relay A responds considerably more rapidly than if the winding I of the relay B were not short circuited. During the energization of the lifting magnet H the relay V is maintained energized over its winding II, the short circuit around its winding I rendering relay V slow-acting, whereby the circuit of the rotary magnet D is maintained opened through the contact v1. If the switching arms of the group selector are positioned on the desired tens 70 level, the relays A and B are energized at the end of the impulse sending so that the relay V is made to retract. During the first lifting step of the selector the closing of the off-normal contact k1 took place, so that 75 the following circuit is completed for the rotary magnet D during the retraction of the relay V after the impulse series has been sent out by the subscriber: earth contact k1, contact p1, left contact of the double acting contact v1, winding of the rotary magnet D, battery. The rotary magnet D is energized and actuates its contact d, whereby an energizing circuit is established for the relay V which runs from the battery over the winding of the lifting magnet H, winding of the relay V, closed d contact, off-normal contact k1, earth. Since, during the first rotary step of the selector, the contact w had been opened, the resistance of the relay V in relation to the 80 resistance of the winding of the lifting magnet H is of such a kind that the lifting magnet H is not energized in this circuit. By energizing the relay V the double acting contact v1 is opened and thus the circuit for 85 the rotary magnet D is interrupted. The rotary magnet D is de-energized and through its contact d opens the circuit for the relay V. The latter, upon retracting, closes the contact v1 whereby the circuit for the magnet 100

D is again closed. This alternate action between the relay V and the magnet D is continued until the testing arm of the selector has found a free line. If the testing arm finds battery over the outgoing line c the relay P is made to energize and opens the circuit for the rotary magnet D through its contact p1. The contact p2 applies earth to the winding I of the relay P. The contacts p3 and p4 switch the connection through.

If the connection is to be released the calling subscriber hangs up his receiver whereby the relays A and B are made to retract. The relay A closes the contact a2 and thereby again establishes the current conditions adapted to cause the relay A to function. Through its contact b1 the release relay B short circuits the winding II of the relay C so that the latter is made to retract as the off-normal contact b2 has already cut off the winding I of the relay C from earth, during the first lifting step of the selector. Through contact c4 the winding of the relay P1 is short circuited so that the latter is de-energized. Consequently contact p1 is closed and the rotary magnet is energized over earth, contact k1, contact p1, left contact at the double acting contact v1, winding D of the rotary magnet, battery. The rotary magnet now moves a step and actuates its contact d whereby a circuit for the relay V is completed over: earth, off-normal contact k1, double back contact d, windings I and II of the relay V, winding H of the lifting magnet H, battery, earth. In this circuit the lifting magnet H does not respond. However, the relay V is energized and actuates its contact v1 whereby the double acting contact is opened and the rotary magnet D is made to de-energize. Thus, in this manner, the switching arms of the group selector are rotated until they reach their extreme rotary position, thereby causing the switch to release in known manner and open contact k1 and close contact k2. Through the retraction of the relay P the switching devices which have been taken into use by the selector GW are released in any known manner.

50 What is claimed is:

1. In a telephone system, an impulse responding relay, a release relay, a circuit for said relays including a source of current, means for interrupting said circuit to deenergize and energize said impulse responding relay, and means controlled by said impulse responding relay in either its energized or deenergized positions for changing the said circuit so as to enable said impulse responding relay to rapidly attain its energized or deenergized position as the case may be, said means being effective also to render said release relay slow acting.

2. In a telephone system, an impulse responding relay, a second relay having two

windings, a trunk line, a battery for talking and operating purposes, an energizing circuit for said relays including one pole of battery, the winding of said impulse relay, the two sides of said trunk line, one winding of said second relay, and the opposite pole of battery in series, and contacts on said impulse relay operated responsive to the energization of said impulse relay for including the second winding of said second relay in said energizing circuit to reduce the current flow in said circuit to enable said impulse relay to more rapidly deenergize when said circuit is opened.

3. In a telephone system, a two conductor subscriber's line extending to an automatic switch, a battery, a line relay in said switch connected between one conductor of said line and one pole of said battery, an impedance in said switch connected between the other conductor of said line and the other pole of said battery, a circuit for shunting said impedance, and contacts on said line relay included in said circuit.

4. In a telephone system, a two conductor subscriber's line extending to an automatic switch, a battery, a line relay connected between one conductor of said line and one pole of said battery, a double wound relay connected between the other conductor of said line and the other pole of said battery, one winding of said double wound relay being normally short-circuited, and contacts on said line relay for opening the short-circuit around said winding to increase the impedance of said double wound relay when said line relay is energized.

In witness whereof, I hereunto subscribe my name this 19th day of July, A. D. 1927.

MAX LANGER.
